TRAY FOR DESK ARTICLES

Henry E. Knaust, St. Louis, Mo.

Filed Oct. 9, 1964, Ser. No. 82,115

Term of patent 14 years

(Cl. D74—5)

FIG. 1

FIG. 2

FIG. 3

I claim:

The ornamental design for a tray for desk articles, substantially as shown.
